UNITED STATES PATENT OFFICE.

HENRY C. SIMONS, OF ODEBOLT, IOWA.

DISK-SHARPENING DEVICE.

1,350,888.

Specification of Letters Patent. Patented Aug. 24, 1920.

Application filed May 10, 1919. Serial No. 296,271.

To all whom it may concern:

Be it known that I, HENRY C. SIMONS, a citizen of the United States, residing at Odebolt, in the county of Sac and State of Iowa, have invented certain new and useful Improvements in Disk-Sharpening Devices, of which the following is a specification.

This invention relates to a disk-sharpening device, and has for its object to provide 10 an apparatus by means of which metallic disks or circular metallic plates, when axially mounted and rotated, may be readily provided with a cutting edge, the parts to be few and simple so that manufacture will 15 be economical and practical, will be effectual in operation, and that durability may be attained.

In the accompanying drawing Figure 1 is 20 a front view of a disk sharpening device embodying my invention. Fig. 2 is a broken away detail view showing a part of a blade-holder. Fig. 3 is an end view of the device. Fig. 4 is a transverse section on line 4—4 of Fig. 1. Fig. 5 is a perspective view of the 25 cutting-blade.

Referring now to the drawing for a more particular description, numerals 6 indicate a pair of strips or elongated supports, these being disposed parallel and adjacent to each 30 other, straps 7 or other equivalent members being secured to the lower sides of the supports for securing them in spaced relation.

Numerals 8 indicate a pair of angle irons, each having its vertical flange secured to the 35 inner edge of a support 6, the horizontal flanges *a* of the angle irons projecting toward each other, whereby a rectilinear space or channel *b* will be formed between the supports.

40 Mounted upon the flanges *a* of the angle irons is a standard 9, this preferably being of inverted U-shape, each of its arms being provided with a foot-member *c* for engaging said horizontal flanges, and by use of suitable keepers or bolts 10, it will be understood that the standard may be secured to the last named flanges, these being engaged at their lower sides by the heads *d* of the bolts. Also it will be understood that by 45 use of the bolts, in a well known manner, the standard may be adjusted longitudinally of the supports, the foot-members *c* having bearings on the flanges *a*.

50 Numeral 11 indicates a second standard, substantially of inverted U-shape, disposed transversely to span the space *b* adjacent to

one end of the supports opposite to the standard 9, said standard 11 having foot-members *e* secured to the supports 6, its upper end being provided with a box 12 for 60 bearings of a stub shaft 13 upon which is mounted a wheel 14 adapted to be actuated by any suitable means for rotating said shaft, the inner end of the latter being provided with a clamping block 15. 65

Threaded in the arms of the standard 9 is a centering-screw 16, adapted to be rotated by its crank *f*, and as thus described, a revoluble movement is provided for any object or article interposed between and carried by the block 15 and centering-screw, as for instance, the disk-holding shaft 17 of an agricultural implement, the disks 18 being secured to and rotating with the shaft. 70

In order that the disks may be sharpened, 75 I provide a cutting-blade 19 which is substantially triangular in cross-section to engage and sharpen the peripheral edges of the disks while the latter are rotating.

Since the disks are not always accurately 80 centered on the shaft and are not, in all instances, disposed at exactly right-angles to said shaft, I provide a staff 20 which may be manually controlled, its lower end being provided with a spike *g* and its upper end 85 being provided with an arm-hold *h*, said staff, between its ends, being provided with a bracket 21 having a projection *k* for supporting the blade 19, a bolt 22 being employed and having a threaded connection 90 with a projection *m* of the bracket for securing the blade 19 in rigid relation with the bracket; and it will be appreciated that an operator, using said member 20 as a crutch, with its spike *g* suitably engaging one of the 95 supports 6, may cause the disks to become sharpened, the staff being disposed at such inclination that one of the longitudinal edges of the blade 19 will engage the periphery of the disk at a suitable inclination 100 to form a sharpened edge, a transverse hand-hold member *n* being also provided for the staff, as an aid in its manual control.

It will be appreciated that the device would be practically inoperative unless the 105 cutting-blade 19 or a blade substantially similar thereto was employed, the fact that this blade is of triangular form in cross-section being of advantage for securing it to the bracket and presenting one of its 110 edges for engaging the circular edge of a disk. Also unless the standard 9 is arranged

for adjustments longitudinally of the supports 6 the device would not be practical since disk-holding shafts similar to the shaft 17, are of various lengths.

5 In operation, the standard 9 is adjusted on the supports so that it will be disposed a suitable distance from the standard 11, depending upon the length of a disk-holding shaft 17. One end of the last-named shaft 10 is then inserted in the clamping-block 15, its opposite end being engaged at its longitudinal axis by the screw 16, and after the set-screw s has been adjusted in the block 15, and the screw 16 made non-revolvole by 15 use of the lock-nut x , the shaft 13 may be actuated for rotating the shaft 17 and its disks, the speed or degree of rotation preferably being moderate or quite limited, so that an operator may effect a suitable engagement of the blade 19 with the disk, as 20 and for the purpose described.

While I have explained construction in detail, I do not wish to be understood as limiting myself in this respect, and changes 25 may be made in form, size, proportion of parts, material to be used and minor details, since the extent or degree of such changes are determined by the scope of the invention as claimed.

30 I claim,—

1. In an apparatus for sharpening the disks of a disk-holding shaft, a pair of elongated supports connected side by side to form a channel therebetween, each support 35 being provided with a flange disposed to overlie a part of said channel, a standard stationary with the supports, a revoluble stub-shaft having bearings on the stationary standard and provided with a clamping- 40 member for supporting one end of the disk-holding shaft, a second standard substantially of inverted U-shape having foot-members engaging said flanges and pro-

vided with a centering-element, means on the foot-members of the second standard 45 adapted to engage said flanges for adjusting said second standard longitudinally of the supports for engagement of said centering element with the opposite end of the disk-holding shaft, a staff, and a cutting- 50 blade triangular in cross-section mounted on the staff, said staff being adapted to be disposed in engagement with one of the supports with its cutting-blade engaging a disk of said disk-holding shaft. 55

2. In an apparatus for sharpening the disks of a disk-holding shaft, a pair of elongated supports connected side by side to form a channel therebetween, each support being provided with a flange overhanging 60 a part of said channel, a standard on the supports, a revoluble stub-shaft with bearings on the standard and having a clamping-member for engaging one end of the disk-holding shaft, a second standard sub- 65 stantially of inverted U-shape provided with a centering-screw and having foot-members engaging said flanges, a pair of bolts each traversing a foot-member of the second standard and having a head in engagement 70 with said flanges, said second standard and said centering screw being movable for engagement of said screw with the opposite end of the disk-holding shaft, a staff, and a cutting-blade angular in cross-section 75 mounted on the staff, said staff being adapted to be disposed in engagement with one of the supports with its cutting-blade engaging a disk of said disk-holding shaft.

In testimony whereof, I have affixed my 80 signature in presence of two witnesses.

HENRY C. SIMONS.
